UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FILLING REPLENISHING LOOM.

Application filed May 2, 1927. Serial No. 188,245.

This invention relates to filling replenishing looms and particularly to means for preventing sloughing or displacement of the yarn upon the filling carriers in the hopper.

5 In the prior patent to John T. Kirk, No. 1,595,045, granted August 3, 1926, there was shown and described an anti-sloughing device which acts upon the mass of filling on the filling carriers in the hopper and prevents endwise displacement thereof. The 10 present invention is a further development of the anti-sloughing device shown and described in the Kirk patent above mentioned.

Filling carriers which are used in the 15 shuttle for laying the filling or weft thread in the shed, are now usually formed with conical or filling wind, and since the conical end portions of the mass of filling on the filling carriers may vary somewhat in size 20 and shape, the present invention is directed to an anti-sloughing device which will automatically conform itself to the contour of the filling on the filling carriers and prevent displacement of the yarn thereon.

25 In accordance with the present invention, the pad which constitutes the filling engaging element of the anti-sloughing device is of generally circular form adapted for use in the well-known rotary hopper, and in 30 order that the pad may automatically conform itself to the filling carriers when they are placed in the hopper, the present invention provides means for supporting the pad for endwise movement between the supports to form cradles or seats in which the 35 end windings of the filling carriers or bobbins rest. The supports for the pad are, in accordance with the present invention, located between the tip end supports for the 40 filling carriers in the hopper and are preferably secured directly to the hopper itself, one at each side of a filling carrier.

The invention and new features thereof will best be made clear from the following 45 description and the accompanying drawings of one good form thereof.

In the drawings:

Fig. 1 is a perspective view at the replenishing side of the loom, showing a hopper 50 for filling carriers containing the present invention;

Fig. 2 is an enlarged sectional view substantially on the line 2—2 of Fig. 1; and

55 Fig. 3 is an enlarged detached detail showing the supports for the pad and the manner

of inserting the pad in the supports for endwise movement relative thereto.

The loom frame 1 may be of usual construction and mounted on the upper part of the loom frame is the hopper stand 2 having 60 the end or cover plate 3 in which is mounted the stud or shaft 4 for the support of the rotary hopper, which comprises the end members 5 and 6. The end member 5 in which the heads 7 of the filling carriers rest, 65 is provided with the usual sockets, and the member 6 is provided with the tip holding devices 8 which cooperate with the sockets in the member 5 for holding filling carriers in the hopper.

70 The tip end supports for the filling carriers may be of any usual or preferred character, and, as shown, comprise the tip end engaging holders 8, which are normally under the influence of springs 10 to cause 75 the tip end holders to press endwise upon the filling carriers. These parts may be of usual construction and need no further explanation.

Extending from the hopper stand is the 80 stud or dead shaft 11 on which is mounted the transference 12 having a downwardly extending portion 13 connected to a dog 14 which on call for replenishment of filling is engaged by a bunter on the lay, as usual in 85 this type of replenishing loom, to transfer a filling carrier from the hopper to the shuttle and eject the depleted filling carrier from the shuttle. These parts, also, may be of usual construction.

90 Secured to the end member 6 of the rotary hopper is the series of pad supports, one of such supports being preferably located between the filling carrier tip supports 8, and mounted in the pad supports for free 95 endwise movement is the pad 15.

Each pad support is preferably formed as a yielding member, and, as shown more clearly in Figs. 2 and 3, comprises the plate 16 having an upstanding arm 17 which may be appropriately secured to the end member 6 of the hopper as by one or more screws 18. The plate 16 is preferably formed of spring metal and has its end portion 19 turned upwardly to provide a loop 20 which embraces 100 the pad 15 transversely between each of the filling carriers in the hopper.

105 The pad supporting loop 20 is formed with a gate 21 which underlies the pad 15, as indicated in Fig. 2, when the pad is in 110

supported position in the loop of the pad supports. The horizontally extending portion 22 of the loop has a shoulder 23 preferably formed by pending the pad support, as shown, so that the end of the gate 21 when in closed position, as indicated in Fig. 2, will underlie the pad in the recess formed by the shoulder.

As hereinbefore mentioned, the pad 15 is of generally circular form and may take the shape of a ring. When the pad 15 is to be placed in position on the pad supports, it is pushed edgewise, Fig. 3, so that the entering edge portion of the pad lifts the yielding gate 21 to permit the pad to be forced into the pad supporting loops, and when the pad is in final position, the gate 21 automatically closes, by reason of its spring action, to thereby maintain the pad in the supporting loops with permissive movement of the pad lengthwise or circularly. The pad is formed of yielding material, such as woven fabric, felt, or other appropriate material, so that when it is placed in the pad supports, as hereinbefore described, it will bend or double up to a degree, and then spread out into its supporting position, as indicated in Fig. 2.

Hoppers of the rotary type for containing filling carriers are charged or supplied from time to time with the filling carriers, and when the filling carriers are placed in the hopper the yielding pad engages the mass of filling on the filling carriers and automatically conforms to the size and shape of the wound mass of filling by the permissive movement of the pad lengthwise in the pad supports.

As described in the Kirk patent, hereinbefore mentioned, the transerrer is provided with a bunter 24, Fig. 1, which engages the filling carriers when the transerrer is operated, and is located inward of the edge of the pad, so that the pad itself does not interfere with the proper transfer of filling carriers during replenishment of filling.

The formation of the pad supports, as hereinbefore described, as of sheet metal or similar material having resiliency of its own, affords an appropriate yielding support for the pad, while the permissive lengthwise movement of the pad in the loops of the pad supports permits the pad to automatically conform to the shape and size of the mass of filling on the filling carriers engaged by it. The gate which closes the loops of the pad supports when the pad has been placed in operative position, prevents edgewise movement of the pad from its loosely supported position in the loops of the pad supports.

What is claimed is:

1. In a filling replenishing loom, the combination of rotary hopper having supports for filling carriers, a pad which bears upon

the mass of wound filling on the filling carriers to prevent sloughing or displacement of the filling, and pad supports provided with loop portions which loosely support the pad for movement relative thereto that the filling engaging portions of the pad may conform to the contour of the mass of filling engaged by it.

2. In a filling replenishing loom, the combination of a hopper for filling carriers, pad supports secured to the hopper between the filling carriers and provided with loop portions and a flexible pad which passes loosely through the loop portions of the supports that the pad may move lengthwise in the loop portions of adjacent supports to form seats in the pad which automatically conform to the shape of the filling mass.

3. In a filling replenishing loom, the combination of a hopper for filling carriers, a pad to bear upon the filling mass on the filling carriers to prevent sloughing or displacement of the filling, and pad supports secured between the filling carriers and provided with loop portions which pass transversely about the pad between the filling carriers and loosely support the pad for endwise movement that the pad may automatically conform to the engaged filling mass.

4. In a filling replenishing loom, the combination of a hopper for filling carriers, a pad to bear upon the filling mass on the filling carriers to prevent sloughing or displacement of the filling, and pad supports secured between the filling carriers and provided with loop portions which pass transversely about the pad, and a gate for closing the loop portions of the supports to prevent release of the pad.

5. In a filling replenishing loom, the combination of a hopper for filling carriers, a pad to bear upon the filling mass on the filling carriers to prevent sloughing or displacement of the filling, pad supports provided with loops to transversely embrace the pad, and gates guarding the entrance to the loops that the pad may be inserted edgewise in the loops.

6. In a filling replenishing loom, the combination of a hopper for filling carriers, a pad to bear upon the filling mass on the filling carriers to prevent sloughing or displacement of the filling, yielding pad supports provided with loops to transversely embrace the pad and loosely support it for movement relative to the loops that the filling engaging portion of the pad may conform to the contour of the mass of filling engaged by it, and yielding gates to permit edgewise movement of the pad into the loops.

7. In a filling replenishing loom, the combination of a hopper for filling carriers, a yielding pad to bear upon the filling mass

of the series of filling carriers in the hopper to prevent sloughing or displacement of the filling, pad supports mounted at intervals to hold the pad in operative position and

5 provided with pad engaging portions which loosely support the pad for movement trans-

versely across the supports that the pad may form loops of varying extent between the supports to automatically conform to the varying contours of the filling mass engaged 10 by it.

In testimony whereof, I have signed my name to this specification.

HARRY A. DAVIS.
